(57) **CLAIM**

The ornamental design for a baseball cap bottle cap, as shown and described.

DESCRIPTION

FIG. 1 is a front perspective view of the baseball cap bottle cap showing my new design;

FIG. 2 is a bottom perspective view thereof;

FIG. 3 is a front elevation view thereof;

FIG. 4 is a rear elevation view thereof;

FIG. 5 is a left side elevation view thereof, the right side elevation view being a mirror image thereof;

FIG. 6 is a top plan view thereof;

FIG. 7 is a bottom plan view thereof; and,

FIG. 8 is a front perspective view thereof, shown in use applied to a beverage bottle.

The broken lines in FIG. 8 showing the baseball cap bottle cap in use illustrate environment and forms no part of the claim.
